UNITED STATES PATENT OFFICE

WALTER C. BOCK, OF NORWOOD, OHIO

DESIGN FOR A SIGN HOLDER

Application filed November 27, 1928. Serial No. 29,044. Term of patent 7 years.

To all whom it may concern:

Be it known that I, WALTER C. Bock, a citizen of the United States, residing at Norwood, in the county of Hamilton, and State of Ohio, have invented a new, original, and ornamental Design for Sign Holder, of which the following is a specification, reference being had to the accompanying drawing, forming part thereof.

I claim:

The ornamental design for a sign holder as shown.

WALTER C. BOCK.
